PLAYER PIANO.

1,404,107.

Specification of Letters Patent. Patented Jan. 17, 1922.

Application filed August 15, 1918. Serial No. 250,008.

To all whom it may concern:

Be it known that I, STANLEY L. FISHER, a subject of the King of Great Britain, residing in Chester, county of Middlesex, State 5 of Connecticut, have invented certain new and useful Improvements in Player Pianos, of which the following is a full, clear, and exact description.

This invention relates to player pianos, 10 and it has special reference to the means for shifting the hammer rest-rail automatically so that the hammers are moved close to the strings when the pumping is soft and moved away from the strings, to give the full hammer stroke, when the pumping is hard. Devices having this broad purpose in view have been used heretofore for relieving the performer of the automatic piano from the necessity of controlling the position of the 15 hammer rest-rail manually and for obtaining a device in which the pianissimo passages are rendered with great delicacy and the fortissimo passages with great power, thus securing the desired contrast of expression. In prior players, however, the means for controlling the hammer rail automatically has been very complicated and expensive in many instances and at the same time unreliable in operation.

30 One of the primary objects of my present invention is to furnish a very simple, inexpensive and efficient device for obtaining the desired movements of the hammer rail.

Another object which I have in view is the 35 provision of a device which is very positive in its action so that repairs and adjustments are not frequently needed, but which, nevertheless, is so located and arranged relatively to the other parts that it is very conveniently accessible if repairs or adjustments have to be made.

Another important feature of my improved expression device consists in the fact 45 that the device for shifting the hammer rest-rail automatically acts on the customary soft pedal stick, so that the construction can be quite simple and so that it is unnecessary to introduce additional operating parts into the piano case above the keyboard, but the 50 operation of this soft pedal stick by the pedal is not interfered with in any way.

Another object of my invention is to provide a very compact, simple and efficient device for connecting the equalizer bellows

of the player with the soft pedal stick in 55 such a manner as to obtain the desired results.

Another improvement resides in the provision of means which enables the performer to place the automatic expression device out 60 of commission if desired and to restore it to the operative condition, at will, by the manipulation of a simple controlling arrangement.

To these and other ends, the invention consists in the novel features and combinations of parts to be hereinafter described and claimed.

In the accompanying drawings.

Fig. 1 is a fragmentary front elevation of 70 an automatic expression device embodying my improvements, with certain parts broken away for the sake of clearness.

Fig. 2 is a section on line 2—2 of Fig. 1 with certain parts omitted, showing the 75 hammer rest-rail in the normal position.

Fig. 3 is a similar view, showing the hammer rest-rail moved towards the strings.

Fig. 4 is a section on line 4—4 of Fig. 1, showing how the rest-rail is moved away 80 from the strings again when the bellows is fully collapsed.

Fig. 5 is a section on line 5—5 of Fig. 1.

Fig. 6 is a bottom plan view of a portion 85 of the key bed, showing the "cut-out" device.

Fig. 7 is a vertical transverse section 90 through the key bed, showing the "cut-out" device or manual controlling device in the inoperative position.

Fig. 8 is a similar view, showing the "cut-out" device in the operative position, in which it prevents the movement of the hammer rail by the automatic means; and

Fig. 9 is a rear elevation of certain parts 95 shown in Fig. 1.

The apparatus shown in the drawings is intended to be located in the lower part of the piano case beneath the keyboard and to cooperate with the usual equalizer bellows located there and with the customary soft pedal stick that is mounted to slide up and down at one side of the piano case, said stick being connected with the soft pedal in such a manner that the former is raised 100 when the pedal is depressed and is lowered 105 when the pressure on the pedal is released.

The bottom of the piano case is shown

at 20, and the ordinary soft pedal stick 21 is, in this case, located at the lefthand end of the instrument and guided in a bracket 22 for vertical movement. The soft pedal 23, which is of the usual type, projects through an opening in the toe-rail 24, and is connected rigidly at its rear end in any convenient manner with a rock shaft 25, journaled in blocks 26 on top of the base board. The rock shaft 25 has a crank arm 27 with a flat, perforated end 28, on which the lower end of the soft pedal stick is adapted to rest as shown in Fig. 2. The soft pedal stick is positioned relatively to the crank arm 27 by means of a pin 29 rigid with the lower end of the stick and adapted to operate in a guide hole 30 in the part 28. When the pedal 23 is depressed, the crank arm 27 is raised in an obvious manner and pushes up the stick 21. The upper end of the stick is connected with the hammer rest-rail 31 in the customary or any preferred manner, so that when the stick is in the position shown in Fig. 2, the rest-rail will hold the hammers 32 at the full distance from the strings 33, to give a loud tone, whereas when the soft pedal stick is raised to the position shown in Fig. 3, the rest-rail will be moved toward the strings to a certain extent to shorten the hammer stroke.

I have not illustrated and described in detail the specific means for mounting the hammer rail and operating it from the soft pedal stick, as the same forms no part of my invention and as any preferred method of actuating the rail from the stick can be employed. When the pedal 23 is released, the weight of the hammer rail and stick causes the latter to move back by gravity to the position shown in Fig. 2, or other means may be employed for restoring the parts quickly to the initial position.

The automatic control of the hammer rail is achieved in the present instance by interposing suitable connections between the customary equalizer bellows E and the lower part of the soft pedal stick. The precise manner in which the bellows E is mounted is not material, and for the sake of simplicity I have shown it mounted on a board or standard 34 rising from the baseboard 20. The front wall 35 of the bellows, which is preferably inclined forwardly and upwardly, is rigid, the movable leaf 36 being arranged at the rear and having its pivotal point lowermost. Fig. 2 shows the bellows in the inflated condition and in Fig. 3 it is shown partly deflated, the upper end of the movable leaf being moved to the right in this instance. The bellows is normally held in the fully inflated condition by the customary spring 37, located at the end farthest from the soft pedal stick, as shown at Fig. 1. At the end of the bellows which is nearest the soft pedal stick, a lever 38 is pivoted

intermediate of its ends on a pivot 39. The pivot 39 may conveniently comprise a pin projecting out laterally from the movable leaf of the bellows and carried by a bracket 40 screwed to the movable leaf at the back, as shown in Fig. 9. The pivot pin 39 is located adjacent the lower edge of the movable bellows leaf and is therefore near the point about which the leaf swings. The lower end of the lever 38 is connected by a short wire link 41 with a crank 42 on the righthand end (Fig. 1) of a small rock shaft 43, journaled in metal blocks 44 on the top of a wood block 45 on the baseboard 20. This rock shaft 43 extends lengthwise of the piano, somewhat above the baseboard and approximately in line with the soft pedal stick. At its lefthand end (Fig. 1) it has a crank 46, which is pivoted at its free end by pin 47 to the lower end of a lifting bar 48. Near its upper end the lifting bar 48 has a slot 49, through which projects a screw or other headed fastening 50 secured in and projecting laterally from the soft pedal stick. When the parts are in the position shown in Fig. 2, the screw 50 is at the bottom of the slot 49 and both the cranks 42-46 project upwardly and forwardly. The lever 38 normally has a substantially vertical position, its upper end being provided with a laterally extending pin 51 extending back of the movable leaf of the bellows. A flat spring 52, secured to the rear face of the movable bellows leaf, has a free end acting against the rear edge of the lever 38 near the upper end of that lever, so that the pin 51 is forcibly held in contact with the movable bellows leaf. In this manner, the lever 38 is connected to the movable leaf at two points, i.e., where the pivot 39 and pin 51 respectively are located, and the lever is adapted to move bodily with the movable leaf. It will be understood, however, that the connection between the upper part of the lever and the movable leaf is a yielding connection, owing to the provision of the spring 52.

When the pneumatic playing mechanism is not in use, the bellows E is opened out to its inflated position by its spring and the parts take the position shown in Fig. 2. The hammer rest-rail 31 is in the normal position and the hammers 32 have the full stroke. If it is desired to play the piano manually, the soft pedal stick can be readily actuated by the pedal in the manner previously described. In this operation the connections from the equalizer bellows do not interfere in any way, as the slot 49 in the lifting bar 48 enables the stick to be raised and lowered without obstruction. When the instrument is played pneumatically by the customary or any preferred pneumatic means, of which the equalizer E is a part, the hammer rail is actuated automatically. When the pumping is light, the blows

of the hammers against the strings are light, owing to the slight tension, and in order to accentuate the pianissimo effect, it is desirable to move the hammers toward the 5 strings so that they will have a shorter stroke, and this is effected as follows: When the bellows E is only slightly collapsed, due to easy pumping, the lever or operating bar 38 is moved forwardly with 10 the movable leaf of the bellows, at the upper end of said lever or bar, while its lower end is shifted slightly towards the rear. As said lower end moves rearwardly, it pulls back the crank 42 through the link 41, therefore 15 by turning the rock shaft 43 and causing the crank 46 to be lifted. The crank 46 carries upward the lifting bar 48 and as the lower edge of the slot 49 impinges against the screw 50, the soft pedal stick or rod is 20 lifted to a certain extent, depending on the force of the pumping. When the bellows is about halfway collapsed, the crank 46 reaches a substantially vertical position in which it and the rod 48 are in alignment 25 with the stick 21, and in this position the stick is raised to the maximum so that the hammer rail will be thrown as far as possible towards the strings and the hammer stroke will be very light. Up to this point, 30 the upward lift of the stick 21 is increased as the tension in the bellows is increased. When, however, the bellows continues its collapse beyond about the halfway point, the lower end of lever 38, in being swung 35 still further to the rear, carries the crank 46 past the dead center, so that the pivot between the crank 46 and rod 48 is carried to the rear of the axis of the stick 21, moving downwardly in an arc corresponding to 40 that through which it has previously been moved upwardly. As the collapse of the bellows continues, the pivot 47 moves downward and backward, pulling down on the bar 48, and as the slot 49 is gradually lowered, the stick 21, with the screw in said slot, is permitted to move back toward the 45 initial position. This initial position is reached at or about the time that the bellows is fully collapsed. The position of 50 the lever 38, lifter bar 48 and associated parts, under these conditions, is shown in Fig. 4. An adjustable stop button 53 with a felted face is mounted in a bracket 54 on the block 45 for the purpose of limiting 55 the rearward throw of the rock shaft 43 by impinging against the upper end of the crank 42.

The spring 52 on the back of the bellows permits a certain yielding of the bar 38 relatively to the bellows and hence there will be no straining of the parts in case they are not nicely adjusted.

It will be seen from the foregoing description that, while the automatic expression device acts on the soft pedal stick, it

does not interfere with the operation of said stick in the ordinary manual playing. While the described arrangement is a very simple one, it provides very effectively for shortening the hammer stroke automatically 70 when the bellows is only slightly collapsed, then lengthening the stroke again when the bellows is more completely collapsed and permitting the hammer rail to move back freely to the normal position when the performer ceases playing. The device is then ready for manual playing of the piano or for further pneumatic playing thereof without the necessity of making any adjustments. 80

Inasmuch as it may be desired to dispense with the action of the automatic expression device at times, I may provide the instrument with a controlling means by which the automatic expression device can be 85 made inoperative or operative at will as desired. For this purpose, the player piano shown in the drawings is provided with a blocking device which preferably cooperates with the upper part of the operating bar 90 38 and which may be moved into and out of its blocking position from the keyboard. In the example shown, an elbow lever 55 is pivoted to the under part of the key bed 56. The lever 55 is arranged to swing in the 95 horizontal plane and it is pivoted at 57. One end, 55^a, is arranged in close proximity to the upper end of the operating bar 38, while the other end of lever 55 is pivoted at 58 to a link 59. The other end of the 100 link is pivoted to a crank 60, on a transverse rock shaft 61 beneath the key bed, said rock shaft being operable by a lever 62 projecting up through a slot 63. This lever 62 has an operating portion disposed above the key 105 bed in front of the keys, where it may be conveniently manipulated. In the position shown in Fig. 7, the elbow lever 55 has its end 55^a swung toward the front of the piano, as shown by the dotted lines in Fig. 6, and 110 it therefore permits the upper end of the bar 38 to pass by the same when the expression device operates in the manner previously described. In this position of the parts, the keyboard lever 62 is thrown to the 115 left of the player. When it is desired to discontinue the operation of the automatic device, the lever 62 is thrown to the right, and the connections described cause the lever 55 to be shifted to the position shown in 120 full lines in Fig. 6. In this position, the bar 38 is in close proximity to the lever 55 and as the bellows is deflated, the bar 38 cannot follow it, owing to the fact that the blocking device prevents forward movement 125 of the upper part of said board. The locking action of the lever 55, when the manipulating lever 62 is thrown to the right, is due to the fact that the crank 60 and the link 59 are in the dead center position, beyond 130

which it is impossible for them to go, as the lever 62 is then at the right hand end of its slot. Consequently, any forward pushing movement on the free end of lever 55 is effectively resisted by the link 59 and the blocked crank 60. Under these conditions, the bellows moves independently of the bar 38, the spring 52 yielding to the necessary extent to permit the full collapse 10 of the bellows, while the bar 38 remains in the substantially vertical, inoperative position. Hence it will be understood that when the "cut-out" device is in the operative position, the stick 21 will not be lifted unless this is done by means of the foot 15 pedal 23.

Various changes may be made in the details of the construction without departing from the scope of my invention as defined in the claims.

It will be observed that the members 46 and 48 pivoted together at 47 form elements of a toggle, which is in a "dead-center" position when the soft pedal stick or rod is 20 in its uppermost position, that is, when the operating bellows is partly collapsed. When the bellows is fully inflated the toggle is at one side of the center position, and as said bellows is moved from the fully inflated 25 to the fully deflated position, the toggle moves to and past the center position carrying the hammer rail towards the strings and then permitting it to move back again.

It is understood that the bellows E is 30 called the equalizer bellows because it is placed intermediate the usual pump and wind-chest (not shown) to equalize the tension. In addition to its usual function it 35 serves as an operating means for the hammer rail, as herein described.

What I claim is:

1. In a player piano, hammer rail mechanism involving a movable operating member and operating means connected to said member to move the hammer rail toward the strings, said operating means being so arranged that on further movement thereof in the same direction the hammer rail is permitted to move away from the strings.

50 2. In a player piano, hammers, strings, a movable hammer rest-rail, a lifting rod for moving said rail toward the strings, and actuating means connected to said rod arranged to lift the same as said means is moved in one direction, said hammer rest-rail being movable away from the strings, as the movement of said actuating means in the same direction is continued.

60 3. In a player piano, hammers, strings, a movable hammer rest-rail, a lifting rod for moving said rail, and actuating means for said rod having an arcuate movement during the preliminary part of which said rod is lifted to move the hammers toward the 65 strings, said actuating means being so ar-

ranged that as its arcuate movement in the same direction is continued the hammers can move away from the strings.

4. In a player piano, hammers, strings, a hammer rest-rail, and actuating means mechanically connected to said hammer actuating means movable in a single direction to shift the hammers toward the strings to a predetermined extent and then away from the strings.

5. In a player piano, a hammer rest-rail, and hammer rest-rail actuating means movable in an arc in a single direction to shift the hammers toward the strings to a predetermined extent and then away from the 75 strings.

6. In a player piano, hammers, strings, a hammer rest-rail, a lifting rod for shifting said rest-rail, a bellows, and connecting means between said bellows and said lifting 85 rod to move the hammers toward the string as the bellows is partially collapsed and to move the hammers away from the strings upon its further collapse.

7. In a player piano, hammers, strings, a hammer rest-rail, a bellows, and connecting means between said bellows and rail to move said rail toward the strings during a preliminary collapse of the bellows and to move the rail away from the strings upon its further collapse.

8. In a player piano, a hammer rail lifting rod, a bellows alongside the same, a shaft having a plurality of cranks, a member connecting one of said cranks with the 100 bellows, and a second member connecting another crank with the lifting rod.

9. In a player piano, a hammer rail actuating member, a bellows having a movable leaf, an operating member carried by said 105 movable leaf, and connecting means between said operating member and said hammer rail actuating member to move the hammers toward the strings during the preliminary part of the collapsing movement 110 of the bellows and to move the hammers away from the strings as it is fully collapsed.

10. In a player piano, a hammer rail actuating member, a bellows having a movable 115 leaf, an operating bar yieldingly mounted on the movable leaf of said bellows, and means of connection between said operating bar and said actuating member.

11. In a player piano, a hammer rail actuating lifting rod, a bellows having a movable leaf, an operating bar carried by the 120 movable leaf of said bellows, a lifting bar having a lost-motion connection with said lifting rod, a rock shaft having cranks, means for connecting one of said cranks with said operating bar, and means for connecting another crank with said lifting bar.

12. In a player piano, a movable hammer rail, a device for shifting said hammer rail, 130

- a bellows having a movable leaf, means associated with said movable leaf for actuating said shifting device, and means for preventing operation of said actuating means by blocking the movement of the same. 5
13. In a player piano, a movable hammer rail, a device for shifting the same, a bellows having a movable leaf, an operating member for said rail-shifting device movably mounted on said leaf, and means cooperating with said operating member to block the movement of the same. 10
14. In a player piano, a movable hammer rail, a device for shifting the same, a bellows having a movable leaf, an operating member for said rail-shifting device movably mounted on said leaf, means cooperating with said operating member to block the movement of the same, and means for manipulating said last named means from the key-board. 15
15. In a player-piano, a movable hammer rail, a device for shifting the same, a bellows having a movable leaf, an operating bar yieldingly mounted on said movable leaf, means for connecting said bar with said rail-shifting device to cause the hammer rail to be shifted by said bellows, and a cut-out device for blocking the movement 20 of said operating bar while permitting the collapse of the bellows. 25
16. In a player piano, hammer rail mechanism including a lifting rod, a toggle connected with said lifting rod, and adapted to lift said rod as the joint of said toggle is moved to the central position, and to permit the lowering of said rod as this joint is moved past the central position, and means for operating said toggle. 30
17. In a player piano, hammer rail mechanism including a lifting rod, a toggle connected with said lifting rod, and adapted to lift said rod as the joint of said toggle is moved to the central position, and to permit 35 the lowering of said rod at this joint is moved past the central position, and means for operating said toggle, including a bellows and lever connections between the bellows and the toggle. 40
18. In a player piano, hammers, strings, a movable hammer rest-rail, a bellows having a movable leaf, means for operatively connecting said rail to said leaf, including a rocking crank, said crank moving said rail towards its strings as said bellows is partially collapsed and moving said rail away from its strings as the bellows is further collapsed. 45
19. In a player piano, hammers, strings, a movable hammer rest-rail, a bellows having a movable leaf, and means operated by said movable leaf for positioning said rest-rail, said means supporting said rail in its closest proximity to said strings when said bellows 50
- is partially collapsed, and moving said rail from said strings as said leaf is moved in either direction from said partially collapsed position. 55
20. In a player piano, hammers, strings, a movable hammer rest-rail, a lifting rod for moving said rail, a pedal for operating said rod, a bellows for operating said rod independently of said pedal, and means for operatively connecting a leaf of said bellows to said rod, said means including a rocking crank for moving said rail towards its strings as said bellows is partially collapsed and for moving said rail away from its strings as the bellows is further collapsed. 60
21. In a pneumatic actuating device, a motor pneumatic having a movable leaf, an actuating lever pivoted thereto at the hinge thereof, and having a lost motion connection with said leaf. 65
22. In a pneumatic musical instrument, a motor pneumatic, an actuating member positively connected thereto for movement in one direction and yieldably connected thereto for movement in another direction. 70
23. In a pneumatic musical instrument, an equalizing pneumatic, an actuating member positively connected to the equalizer for movement in one direction and yieldably connected to the equalizer for movement in another direction. 75
24. In a pneumatic actuating device, a motor pneumatic having a movable leaf, an actuating member yieldably connected thereto to normally be moved thereby, and means to prevent movement of said actuating member upon movement of said movable leaf. 80
25. In a pneumatic actuating device, an actuating member, a pneumatic, and connections between said member and said pneumatic to move said member in opposite directions during a continued movement of the movable leaf of the pneumatic in one direction. 85
26. In an expression device, an expression controlling member, an actuating pneumatic therefor, and connections between said member and said pneumatic to move said member in opposite directions during a continued movement of the movable leaf of the pneumatic in one direction. 90
27. In a player piano, a piano action including hammers and strings, means to move said hammers relatively to the strings to vary the stroke thereof, an actuating pneumatic and connecting means between said pneumatic and moving means to move said hammers toward the strings during the initial collapse of the pneumatic and away from the strings upon its further collapse. 95
- In witness whereof I have hereunto set my hand on the 5th day of August, 1918. 100

STANLEY L. FISHER.

Certificate of Correction.

It is hereby certified that in Letters Patent No. 1,404,107, granted January 17, 1922, upon the application of Stanley L. Fisher, of Chester, Connecticut, for an improvement in "Player Pianos," an error appears in the printed specification requiring correction as follows: Page 4, lines 71 and 72, claim 4, for the words "actuating means" read *rest-rail*; and that the said Letters Patent should be read with this correction therein that the same may conform to the record of the case in the Patent Office.

Signed and sealed this 14th day of February, A. D., 1922.

[SEAL.]

KARL FIENNING,
Acting Commissioner of Patents.
